HARNESS MOTION FOR LOOMS

Carl F. Schlegel, Brighton, N. Y., assignor to The Schlegel Manufacturing Company, Rochester, N. Y., a corporation of New York

Application September 2, 1937, Serial No. 162,174

9 Claims. (Cl. 139—69)

This invention relates to looms and more particularly to high speed looms.

An object of the invention is the provision of an improved and more satisfactory harness motion for such looms.

Another object is the provision of a harness motion which will operate reliably and effectively at high speed, to produce an even or smooth shed.

Still another object is the provision of such a harness motion which is relatively simple, easy to construct, and sturdy in operation, so that it is not likely to get out of order.

To these and other ends the invention resides in certain improvements and combinations of parts, all as will be hereinafter more fully described, the novel features being pointed out in the claims at the end of the specification.

In the drawings:

Fig. 1 is a diagrammatic side elevation of a loom with the harness motion of the present invention applied thereto, showing the parts in one position, with no shed formed in the warp strands;

Fig. 2 is a front elevation of the harness frames and associated parts;

Fig. 3 is a view similar to Fig. 1 with the parts in a different position, forming a shed in the warp strands;

Fig. 4 is a side elevation of the mechanism for operating certain parts of the harness motion;

Fig. 5 is a side view of the principal parts of the harness motion, in a position corresponding to that of Fig. 1;

Fig. 6 is a vertical section taken substantially on the line 6—6 of Fig. 5;

Fig. 7 is a view similar to Fig. 5 illustrating the parts in a position corresponding to that of Fig. 3;

Fig. 8 is a plan of part of the mechanism shown in Fig. 7;

Fig. 9 is an end view of the chain drum and pattern chain thereon;

Fig. 10 is a perspective view of one of the latches for latching certain operating parts of the harness motion to each other, and

Fig. 11 is a rear elevation of the main parts of the harness motion.

The same reference numerals throughout the several views indicate the same parts.

The parts of the loom other than the harness motion may be constructed in any known way, and the present invention is independent of the construction that may be selected for such parts of the loom, so that the loom need not be described in detail. It may include frame parts 11 (Figs. 1 and 3) carrying suitable means for sup-

plying warp strands 13 which are led upwardly, over a roller 15, and then forwardly as at 17 to form the warp of the fabric being woven. The completed fabric is led forwardly and downwardly over a breast roll 19 to pulling rolls 21 and is then wound up on any suitable cloth roll. The weft or filling is laid across the warp strands by any suitable known means, such as by the needle 23, if a needle loom or shuttleless loom is employed, or by any suitable shuttle if a loom of the shuttle type is employed. Since the harness motion of the present invention is well adapted for work at high speed, it may be used advantageously on needle looms, most of which operate at high speed, but it may also be employed, of course, on lower speed looms, such as looms employing conventional shuttles.

The warp strands 17 pass through the heddles 25 (Fig. 2) secured to the heddle frames or harness frames 27, and these harness frames 27 are raised or lowered from the neutral positions shown in Fig. 1, to form the shed as shown in Fig. 3, by means of the harness motion which forms the present invention.

Near the front of the loom and below the breast roll 19 is a transverse shaft 31 on which are pivotally mounted a series of bell crank levers, one for each of the harness frames 27. Each bell crank lever has a downwardly extending arm 33 and a rearwardly extending arm 35, and the downwardly extending arm 33 is provided with arcuate guiding flanges 37 projecting laterally at each side of the arm 33 for contact or substantial contact with the similar flanges of the adjacent bell crank levers, as shown in Fig. 11, to hold the levers against side sway or tilting, while nevertheless permitting each lever to oscillate about its shaft 31 independently of the other levers.

The rearwardly extending arm 35 of each bell crank lever is connected by a link 39 with its associated one of the harness frames 27. In order to form a smooth or even shed, it is apparent that those harness frames 27 which are farther from the roll 19 should be moved upwardly or downwardly to a greater extent than those harness frames which are closer to the breast roll. This is easily accomplished by the present mechanism, for the harness frames which are farther from the breast roll 19 are connected by the links 39 to their respective bell crank arms 35 at points farther from the shaft 31. Hence, if all of the bell cranks be oscillated to the same uniform angular extent, those harness frames which are toward the rear of the loom will be given a

greater throw or range of travel than those harness frames closer toward the front of the loom, with the result that the shed produced in the warp strands will be approximately uniform and 5 even, as shown diagrammatically in Fig. 3.

The frame of the loom is provided with suitable horizontal guideways 43, and in these guideways are mounted two actuating bars extending transversely of the loom, the front one of which 10 bars is designated by the numeral 45 and the rear one of which is designated 47. These bars lie substantially in a common plane, and are reciprocated forwardly and rearwardly, toward and away from each other, in this common plane, 15 by suitable mechanism such as that shown for example in Figs. 1, 3, and 4. A rotating shaft 51, which may be the main drive shaft of the loom or which may be driven in timed sequence with the main drive shaft, is provided with two 20 eccentrics 55 and 57 set at 180° to each other. The eccentric strap embracing the eccentric 55 is connected by a link 59 to a lever 61 fixed to a transverse shaft 63, while the eccentric strap on the other eccentric 57 is similarly connected by 25 a link 65 to a lever 67 fixed to a transverse shaft 69.

The shaft 63 extends across the machine and is provided with two arms 71 extending upwardly therefrom, at opposite sides of the machine, the upper end of each arm having a slot 30 for engaging a pin 73 on the end of the actuating bar 45. One of the arms 71 at one side of the machine may be integral with the arm 61, if desired. Similarly, the other cross shaft 35 69 is provided with two upwardly extending arms 75 at opposite sides of the machine (one of which may be integral with the arm 67) which have slots engaging pins 77 on the ends of the other actuating bar 47. With this arrangement 40 rotation of the shaft 51 will move the front actuating bar 45 rearwardly and the rear actuating bar 47 forwardly, so that the two bars approach each other, during half of each complete revolution of the shaft 51, and then during the other 45 half of such revolution the front actuating bar 45 will be moved forwardly and the rear actuating bar 47 will be moved rearwardly, shifting the bars away from each other. Thus the two actuating bars will be reciprocated back and forth, toward and away from each other, always 50 remaining substantially in a common plane and substantially parallel to each other.

The forward actuating bar 45 is provided on its upper surface, and near its forward edge, 55 with a transverse groove 81 having an undercut rear edge as shown in Figs. 5 and 7, while the rear actuating bar 47 has a similar transverse groove 83 on its upper surface near its rear edge, the forward edge or wall of which transverse 60 groove is undercut.

To the bottom of the arm 33 of each bell crank lever is pivotally connected, at 85, what may be termed a hook bar 87, extending both forwardly and rearwardly from the pivot 85, in the direction of travel of the actuating bars 45 and 47. The rear arm of the bar 87 is somewhat longer than the forward arm thereof, as shown in Fig. 5. Each arm, at its extremity, is provided with a downwardly extending hook, the forward one 65 being indicated at 89 and the rear hook being shown at 91. These hooks 89 and 91 are so placed that they are alined with the transverse grooves 81 and 83 of the actuating bars 45 and 47, whenever the bell crank 33 is in its central or 70 neutral position and when the actuating bars 45

and 47 are in their positions closest to each other. The pivot 85 is at such an elevation with respect to the horizontal plane in which the actuating bars 45 and 47 move, that the hooks 89 and 91 cannot both be engaged in the respective grooves 5 81 and 83 at the same time, but either hook alone may be depressed into its corresponding groove when the parts are in proper position, and this will raise the other hook at the other end of the bar 87 out of engagement with the 10 other transverse groove. Thus each bar 87 may be hooked to either one of the actuating bars 45 and 47, but cannot be hooked to both of them at once.

Extending transversely across the loom, at an 15 elevation somewhat above the actuating bars 45 and 47 and the hook bars 87, are two stationary bars 93 and 95, respectively. The bar 95 supports a transverse pivot shaft 97 on which are pivoted a series of forwardly and downwardly 20 extending fingers 99, one overlying each of the hook bars 87 and riding on the top thereof. Suitable springs 101 press downwardly on the fingers 99 with a substantial pressure, so that these arms in turn, constantly press downwardly with substantial force on the rear ends of the arms 87. Hence, in the absence of a superior force producing an upward thrust on the rear ends of the hook bars 87, the rear ends of all of these hook bars will be depressed by the springs 101 30 and fingers 99, and the hooks 91 will be engaged in the groove 83 of the actuating bar 47, so that the hook bars 87 will be hooked to the actuating bar 47 and will move backwardly and forwardly with the actuating bar. When the actuating bar 35 47 moves rearwardly from the position shown in Fig. 5 to the position shown in Fig. 7 this will draw rearwardly on the hook bars 87 which are hooked to the actuating bar, which will cause rearward movement of the bell crank arms 33 40 and upward movement of the bell crank arms 35, raising the harness frames 27 connected to those bell cranks.

In order to raise the rear ends of the hook bars 87 whenever required, to unhook them from the 45 actuating bar 47 and hook them to the actuating bar 45, there may be provided a pattern chain shaft 105 carrying a chain drum 107 having end flanges 109. A pattern chain, which may be of suitable known construction, runs over this drum, 50 the cross pins 111 of the chain being connected to each other by links 113, and the pins being received in notches 115 in the end flanges 109, so that as the drum rotates, the chain cannot slip on the drum but will be fed around with it. 55 The cross pins 111 carry tubular members of different diameters, the larger ones 117 of which may be denoted as risers and the smaller ones 119 may be called sinkers. These risers and sinkers are arranged in any desired manner or 60 sequence on the pins 111, to produce the desired pattern in the fabric being woven. The pattern chain may, as usual, be of any desired length. When the pattern is simple, it may be a relatively short chain extending tightly around the 65 periphery of the drum 107, 109, as shown in Fig. 5, or it may be a longer chain as shown in Fig. 9, having a portion hanging loosely down below the drum.

The chain drum is driven with a step by step 70 motion in timed sequence with the operation of the actuating bars 45 and 47 and with the other parts of the loom. For instance, the shaft 51 on which the eccentrics 55 and 57 are mounted, may be provided with a driving crank 121 and a lock- 75

ing disk 123, both cooperating with a Geneva member 125 in known manner, to turn this Geneva member step by step, one step for each revolution of the shaft 51. A sprocket 127 secured to the Geneva member 125 may drive a chain 129 which runs around a sprocket 131 on the chain drum shaft 105, thus turning the drum in proper timed sequence to the operation of the other parts.

10 The shaft 105 is so placed with relation to the horizontal plane in which the actuating bars 45 and 47 operate, that when a sinker 119 is brought into position beneath one of the hook bars 87, it does not interfere with the tendency of 15 the spring 101 to depress the rear end of this hook bar, and consequently, whenever a sinker is brought into effective position beneath one of the hook bars, the rear end of the hook bar will be depressed and the hook 91 thereon will be 20 engaged with the slot 83 on the actuating bar 47. Whenever one of the risers 117 is brought into effective position beneath one of the hook bars 87, the size of this riser is such that it will press upwardly on the under side of the hook bar 25 and raise the rear end of the hook bar against the force of the spring 101, moving the hook 91 upwardly out of the groove 83 and depressing the hook 89 into the groove 81 of the forward actuating bar 45, thus hooking this particular 30 hook bar 87 to the forward actuating bar 45 and unhooking it from the rear actuating bar 47. The driving mechanism for driving the pattern chain is so timed with respect to the movements of the bars 45 and 47, that a new cross pin 111 35 of the chain moves to the uppermost position at the top of the drum 107 at or substantially at the instant that the forward actuating bar 45 reaches its rearmost position and the rear actuating bar 47 reaches its most forward position, 40 these being the positions shown in Fig. 5.

Since the hooks 89 and 91 have undercut sides to cooperate with the undercut rear and front walls, respectively, of the grooves 81 and 83, they will be held effectively in hooked relationship to 45 the actuating bars during the travel thereof, with little danger of accidental disengagement so long as either of the bars 45 and 47 exerts a substantial pull on the bar 87. When the bars 45 and 47 begin to move toward each other, however, 50 there is no longer a pull on the inclined or undercut faces of the hooks, and the bars 87 may become disengaged from the actuating bars, especially from the bar 45, since the springs 101 55 are constantly tending to produce such disengagement. Hence, it may be desirable to employ latches to latch the hooks positively in the grooves 81 and 83, such latches being especially desirable in connection with the groove 81 on the bar 45.

60 Such latches may be of the form best shown in Figs. 5, 7, and 10. The forward actuating bar 45 is provided with a transverse pivot shaft 145 on which is pivoted a series of latch members 147, one of which is arranged directly opposite the 65 front end of each of the hook bars 87. These latch members 147 are located in slots or cut-out portions of an upstanding flange 149 at the front edge of the bar 45, which flange serves to guide the latches 147 laterally and prevent lateral dis- 70 placement thereof. Leaf springs 151 are secured to the underside of the bar 45 as by means of rivets or screws 153, and extend up the forward sides of the latches 147, constantly tending to shift the upper ends of the latches rearwardly to 75 the effective latching position illustrated in Fig.

7, in which a ledge or shoulder 155 on each latch overlies the upper forward corner of its associated hook bar 87 and prevents the hook 89 of this hook bar from rising upwardly out of the groove 81. A sharp angular lower rear corner 154 on 5 each latch 147 contacts with the horizontal portion of the spring 151 near the rivets or screws 153 to limit movement of the latch in an effective latching direction. As the bar 45 moves rearwardly, and just before it reaches the rearward 10 limit of its travel, the upper end of each latch member 147 strikes against the stationary cross bar 93, which tilts the upper ends of all of these latch members 147 forwardly and releases the latches as shown in Fig. 5, so that the forward 15 ends of any hook bars 87 which are hooked into the groove 81 may be released therefrom, and so that any hook bars not already hooked into the groove 81 but which should now be hooked thereinto, may be depressed into the groove 81 without interference from the latches. Then, as the actuating bar 45 moves forwardly at the beginning of its next cycle of travel, the upper ends of all of the latches 147 will ride out from under the stationary bar 93 and the springs 151 will 20 immediately move all of these latches to effective latching position as shown in Fig. 7, so that they will latch the forward ends of all of the hook bars 87 which have been hooked to the actuating 25 bar 45. 30

Similar latch means are provided on the rear actuating bar 47, for cooperation with the rear ends of the hook bars 87. The latch means on the bar 47 may be identical with the latch means on the bar 45, although faced, of course, in the opposite direction, and the parts on the latch bar 47 are designated by the same reference numerals 145 to 153 used for the corresponding parts on the bar 45, with the addition of the letter "a" 35 to each such reference numeral. The latches 40 147a on the actuating bar 47 are operated by the stationary cross bar 95 in the same way in which the latches 147 on the bar 45 are operated by the stationary bar 93. 45

It is seen that this harness mechanism is well 45 adapted to high speed operation, because the hook bars 87 are positively latched to the actuating bars 45 with which they are engaged from time to time, without any possibility of accidental disengagement therefrom. No matter how fast 50 the bars 45 and 47 may move backwardly and forwardly in their reciprocating cycles, the hook bars 87 cannot become accidentally disengaged therefrom, but are engaged with and disengaged from the respective actuating bars only in accordance with the requirements of the weaving pattern as determined by the risers and sinkers on the pattern chain. Gravity is not relied upon 55 for engagement or disengagement of the hook bars 87 at any stage of the operating cycles, which is another reason why this mechanism is well 60 adapted to high speed operation. The spring 101 can be made sufficiently strong to disengage the hooks 89 from the bar 45 and engage the hooks 91 with the bar 47 in a minimum of time, while 65 the reverse engagement (that is, disengagement of the hooks 91 and engagement of the hooks 89) is likewise accomplished in a minimum of time by the positive upward force produced by the risers on the pattern chain coming into engagement with the under side of the hook bars 87. In addition to having these features which 70 promote rapid operation to meet the requirements of a high speed loom, this harness motion is also of relatively simple and sturdy construction, so 75

that it is easy to maintain in proper operative condition, and not likely to get out of order.

The operation of each part of the construction has been individually described, but a brief review 5 of the entire operation will now be given. Assume that the parts are in what may be termed the neutral position shown in Fig. 1, with the forward actuating bar 45 at the rear end of its path of travel and with the rear actuating bar 47 at 10 the forward end of its path of travel. The bell cranks 33, 35 and the harness frames 27 are all in a central or neutral position, and the latches 147 and 147a are all unlatched, by reason of the fact that they are now beneath the stationary 15 bars 93 and 95. The hook bars 87 will be in positions determined by the risers and sinkers on that pin 111 of the pattern chain which is now at the top of the chain drum, directly beneath the hook levers 87. That is, any hook lever 87 20 which is directly over a riser will have its rear end raised thereby and its forward end will be depressed so that the hook 89 will be in the groove 81 of the forward actuating bar 45. This is the position shown in Fig. 5 with respect to the hook 25 bar 87 which is closest to the eye of the observer.

Any hook bar 87 which is directly over a sinker 119 of the pattern chain will not be raised at its rear end, and consequently the spring 101 of this hook bar 87 (aided to some extent by gravity) will 30 cause the rear end of this hook bar to be depressed, engaging the hook 91 thereof with the groove 83 of the rear actuating bar 47, and raising the front hook 89 thereof out of engagement 35 with the front actuating bar 45. This is the condition shown in Fig. 5 with respect to that one of the hook bars 87 which is farthest from the eye of the observer.

The bars 45 and 47 now move away from each other. The hook bar 87 closest to the eye of the 40 observer, being hooked to the forward actuating bar 45, will be drawn forward by the forward motion of the bar 45, which will pull forwardly on the connected bell crank arm 33, pulling downwardly on the bell crank arm 35, and lowering 45 the harness frame 27 connected to this bell crank. During the early part of this forward travel of the actuating bar 45, the latches 147 will ride out from under the stationary bar 93 and all of the latches will be moved to effective 50 position over the forward ends of those hook bars 87 which are hooked to the actuating bars 45, preventing accidental disengagement.

At the same time that the actuating bar 45 moves forwardly, the other actuating bar 47 will 55 move rearwardly. All of the hook bars 87 which have been hooked to the rear actuating bar 47 will thus be drawn rearwardly by this actuating bar, which will move their connected bell crank arms 33 rearwardly, and move the connected bell 60 crank arms 35 upwardly, raising the corresponding harness frames 27. Near the beginning of this rearward movement, the latches 147a will become effective to latch the rear ends of the hook bars 87 against accidental disengagement, 65 just as in the case of the latches 147. The positions of the parts when the forward and rear actuating bars 45 and 47 are near their extreme forward and rear positions, respectively, are shown in Figs. 3 and 7.

70 The forward motion of certain of the harness frames 27 and downward movement of the other harness frames, produced as above described, forms a shed in the warp strands 17, as shown in Fig. 3. If the loom is a needle loom, the needle 75 23 now lays the weft or filling strands through

the shed, or if the loom is a shuttle loom, the shuttle does the same. The usual reed or batten now beats up the newly laid weft strands, and the bar 45 moves rearwardly and the bar 47 moves forwardly again, to their neutral or initial positions shown in Figs. 1 and 5, and just before they reach these neutral positions, the latches 147 and 147a are tripped or unlatched by contact with the bars 93 and 95, so that by the time the neutral positions of the bars 45 and 47 are reached, the 10 hook bars 87 are free to be unhooked and rehooked according to any desired pattern. Substantially at the same time that the neutral positions of the bars 45 and 47 are reached, the Geneva member 125 is turned one step to bring 15 a fresh cross bar 111 of the pattern chain into cooperating relation to the hook bars 87. The risers and sinkers 117 and 119 on this fresh cross bar 111 will now control the hook bars 87 during the next cycle of operation. Some of 20 the hook bars 87 which have been hooked to one of the actuating bars may remain hooked to this same actuating bar during the next cycle of operation, and some or all of the hook bars may be shifted to hook them to the other actuating 25 bar than the one to which they were hooked during the previous cycle, all as determined by the risers and sinkers on the pattern chain, and in accordance with the particular pattern which it is desired to weave. The bars 45 and 47 then 30 move away from each other again, carrying with them the hook bars 87 which are respectively hooked thereto, and the cycle of operation is repeated ad infinitum.

In the embodiment of the invention above described as a preferred example, two actuating bars 45 and 47 are employed, one of which serves to move the harness frames upwardly and the other of which moves them downwardly. Those skilled in the art will readily appreciate that if 35 it is required to move the harness frames in only one direction from their neutral position, instead of two directions, then one of the actuating bars can be omitted, and the remaining parts would act in substantially the same way above described. 40 With only a single actuating bar, the risers on the pattern chain would either disconnect the hook bars from or connect them to the single actuating bar (depending upon which of the two bars was omitted) and when any hook bar was 45 connected to the actuating bar, the corresponding harness frame would be raised or lowered, as the case may be, whereas a hook bar not connected to the actuating bar would not produce 50 any movement of the corresponding harness frame.

While one embodiment of the invention has been disclosed, it is to be understood that the inventive idea may be carried out in a number of ways. This application is therefore not to be limited to the precise details described, but is intended to cover all variations and modifications thereof falling within the spirit of the invention or the scope of the appended claims.

I claim:

1. Loom harness motion including two actuating bars each having hook receiving recess means therein, means for moving said bars toward and away from each other, a plurality of hook bars each having hook means for entering the recess means in and thereby becoming operatively engaged with either of said actuating bars, so that when one of said hook bars is engaged with one of said actuating bars it will be moved thereby in one direction during part of an operating cycle and when engaged with the other of said actuat- 75

ing bars it will be moved thereby in an opposite direction during the same part of an operating cycle, latch means mounted on and movable bodily with each of said actuating bars for latching said hook bars to the respective actuating bars with which they are engaged, movable pattern chain means for determining with which of said actuating bars each of said hook bars will engage from time to time, a plurality of harness frames, and means operatively connecting said hook bars to said harness frames to move said harness frames by movement of said hook bars.

2. Loom harness motion including an actuating member having hook receiving recess means therein, means for moving said actuating member back and forth through a cycle of operation, a plurality of hook bars each having hook means for entering and withdrawing from the recess means in said actuating member and thereby becoming operatively engaged therewith and disengaged therefrom, movable pattern chain means for controlling engagement of said hook bars with and disengagement thereof from said actuating member, latch means for positively holding in effective engagement with said actuating member during part of the operating cycle those hook bars which have theretofore been engaged with said actuating member, a plurality of harness frames, and means operatively connecting said hook bars to said harness frames to move said harness frames by movement of said hook bars.

3. Loom harness motion including an actuating bar, means for moving said actuating bar back and forth through a cycle of operation, a hook bar extending in a direction generally transverse to said actuating bar, cooperating hook means on said hook bar and said actuating bar for detachably connecting said hook bar to said actuating bar to be moved thereby, latch means mounted on and movable bodily with one of said bars for latching said two bars to each other to prevent disconnection thereof, means for rendering said latch means ineffective during a part of each cycle of operation of said actuating bar, pattern chain means cooperating with said hook bar during said part of each cycle of operation to determine whether said hook bar shall be connected to or disconnected from said actuating bar during the next cycle of operation, a harness frame, and means operatively connecting said harness frame to said hook bar to be moved thereby.

4. Loom harness motion including an actuating bar, means for moving said actuating bar back and forth through a cycle of operation, a hook bar extending in a direction generally transverse to said actuating bar, cooperating hook means on said hook bar and said actuating bar for detachably connecting said hook bar to said actuating bar to be moved thereby, latch means mounted on and movable bodily with one of said bars for latching said two bars to each other to prevent disconnection thereof, means for rendering said latch means ineffective during a part of each cycle of operation of said actuating bar, spring means tending to connect said hook bar to said actuating bar during said part of each cycle of operation, a movable pattern chain having risers thereon, means for moving a fresh portion of said chain into cooperative relation to said hook bar during said part of each cycle of operation, said chain being so placed with respect to said hook bar that a riser on the portion of said chain moved into cooperative relation to said hook bar will contact with said hook bar and disconnect it from said actuating bar or hold it

disconnected if it were previously disconnected therefrom, a harness frame, and means operatively connecting said harness frame to said hook bar to be moved thereby.

5. Loom harness motion including two actuating bars mounted for movement toward and away from each other, means for moving both of said bars concomitantly toward and away from each other, a plurality of hook bars each extending in a general direction from one of said actuating bars to the other, means pivotally mounting each of said hook bars for oscillation about an axis intermediate its length, cooperating hook means on said hook bars and actuating bars for detachably connecting each hook bar to either of said actuating bars to be moved thereby, said axis of oscillation of each hook bar being so placed that movement of each hook bar into connecting engagement with either one of said actuating bars disconnects it from the other of said actuating bars, a plurality of latches mounted on each actuating bar, one for each of said hook bars, each latch being movable from an ineffective unlatched position to an effective latched position in which it holds its associated hook bar, if connected with the actuating bar on which the latch is mounted, against disconnection therefrom, means for holding each of said latches in unlatched position during a part of an operating cycle of movement of said actuating bars, pattern control means effective during said part of an operating cycle while said latches are unlatched, for causing shifting of said hook bars into connecting engagement with either selected one of said actuating bars in accordance with the requirements of the pattern to be woven, means for holding each of said latches in effective latched position during substantially the rest of said operating cycle of movement, a plurality of harness frames, and means operatively connecting each of said hook bars to one of said harness frames to move each harness frame in one direction or the other by the movements of the connected hook bar.

6. A construction as set forth in claim 5, in which said means for holding said latches in effective latched position comprises spring means constantly tending to hold said latches in said position, and in which said means for holding said latches in unlatched position comprises members for engaging said latches at a predetermined point in said operating cycle to unlatch said latches against the force of said spring means.

7. Loom harness motion including two actuating bars mounted for movement toward and away from each other, means for moving both of said bars concomitantly toward and away from each other, a shaft spaced from said actuating bars, a plurality of bell crank levers mounted on said shaft, each of said levers having an arm extending in a general direction toward said actuating bars, a plurality of hook bars each extending in a general direction from one of said actuating bars to the other, each of said hook bars being pivotally mounted adjacent the end of said arm of one of said bell crank levers for oscillation about an axis intermediate the length of said hook bar, cooperating hook means on said hook bars and actuating bars for detachably connecting each hook bar to either of said actuating bars to be moved thereby, said axis of oscillation of each hook bar being so placed that movement of each hook bar into connecting engagement with either one of said actuating bars disconnects it from the other of

said actuating bars, spring means constantly tending to engage each hook bar with one of said actuating bars and disengage it from the other actuating bar, a pattern chain having a 5 plurality of sections, each section being adapted to carry one or more protruding portions in accordance with the requirements of the pattern to be woven, means for moving said pattern chain in timed relation with said actuating bars to bring 10 a fresh section of said chain into cooperative relation to said hook bars at a predetermined time in each cycle of movement of said actuating bars, said chain being so placed with relation to said hook bars that any of said protruding portions on the section of chain newly brought into 15 cooperative relation to said hook bars will contact directly with those hook bars corresponding to said protruding portions and move such hook bars against the action of said spring means to 20 disengage such hook bars from said one of said actuating bars and engage them with said other actuating bar, unless they are already thus engaged, a plurality of harness frames, and means operatively connecting each of said bell crank 25 levers to one of said harness frames to move the harness frames in accordance with movement of the hook bars.

3. Loom construction including a main frame, breast means adjacent the front of said frame, 30 a plurality of harness frames mounted on said main frame rearwardly of said breast means for upward and downward movement relatively to said main frame, a shaft extending transversely of said main frame at an elevation below said breast means, a plurality of bell cranks mounted 35 for oscillation on said shaft, each of said bell cranks including an arm extending downwardly from said shaft and another arm extending rearwardly from said shaft, means operatively connecting the rearwardly extending arm of each bell crank to one of said harness frames, a bar 40 pivotally connected to the downwardly extending arm of each of said bell cranks, an actuating

member extending transversely of said main frame and movable rearwardly and forwardly adjacent all of said bars and approximately in a horizontal plane, pattern controlling chain means including risers for contacting directly 5 with said bars to shift said bars to connect any of said bars to or disconnect them from said actuating member from time to time according to the requirements of the pattern to be woven, said actuating member imparting movement to any 10 of said bars which are operatively connected thereto and thus causing movement of the corresponding harness frames, and pivoted latch means carried by said actuating member for positively latching to said member, during part of 15 the movement thereof, those of said bars which are connected thereto.

9. Loom construction including a main frame, breast means adjacent the front of said frame, a plurality of harness frames mounted on said 20 main frame rearwardly of said breast means for upward and downward movement relatively to said main frame, a shaft extending transversely of said main frame at an elevation below said breast means, a plurality of bell cranks mounted 25 for oscillation on said shaft, each of said bell cranks including an arm extending downwardly from said shaft and another arm extending rearwardly from said shaft, means operatively connecting the rearwardly extending arm of each 30 bell crank to one of said harness frames, lateral flanges on said downwardly extending arms of said bell cranks at points spaced substantially below said shaft for sliding engagement with the flanges of adjacent bell cranks to hold said 35 downwardly extending arms against lateral movement with respect to each other, and means for causing movement of said downwardly extending arms in accordance with the requirements of the pattern to be woven, to cause corresponding movement of the associated harness frames. 40
